Specification for Design.

Patented Feb. 11, 1919.

Application filed October 12, 1918 Serial No. 257,893. Term of patent 7 years.

To all whom it may concern:

Be it known that I, JOHN G. CHAPMAN, a citizen of the United States, residing at Port Washington, in the county of Nassau and State of New York, have invented a new, original, and ornamental Design for an Edging, of which the following is a specification, reference being had to the accompanying drawing, which shows a strip of edging embodying my new design in elevation.

I claim:—

The ornamental design for an edging, as shown.

JOHN G. CHAPMAN.
